COIN AND SLUG SEPARATING DEVICE

Walter A. Tratsch and William Patzer,
Chicago, Ill.Original application June 18, 1936, Serial No.
85,879. Divided and this application June 10,
1938, Serial No. 212,891

3 Claims. (Cl. 194—100)

This invention pertains to coin and slug separating devices and more particularly to a coin testing means, commonly referred to as a coin chute, which includes an improved rebound means from which certain coin elements are adapted to rebound or bounce for movement past an exit opening or the like.

Viewed from another aspect, it is an important object of the invention to provide a coin chute having a descending coin passage with a drop-out opening between its ends and an improved rebound means in the path of a coin descending the passage and from which certain proper coin elements may rebound to carry them safely past the drop-out opening so that they may reach the end of the passage, spurious and improper coin elements moving into the drop-out opening because the material of which they are made is such that they do not have sufficient kinetic energy at the time they strike the rebound means to carry them past the drop-out opening, or such that much of their energy is lost in the impact with the rebound means, and hence not available to carry these coin elements safely past the drop-out.

Another object of the invention is the provision of means providing a descending coin passage having an entrance and an exit end and a sidewise drop-out opening between said ends and into which certain spurious or improper coin elements are caused to move as a result of gravitating impact with a rebound anvil positioned in advance of the drop-out opening.

Another and more specific object is the provision in a coin chute of improved rebound means in the form of an anvil mounted in the path of descending coin elements and having an elongated downwardly tilted contact surface of wedge-like cross section with a ridge portion for the wedge part of less width than the edge of the coin, such that coin elements formed of a material of less than predetermined hardness and related physical characteristics will, when deposited in the chute, strike edgewise against the wedge-like rebound surface of the anvil and be temporarily or permanently dented or deformed as a result of the impact, so that the coin element will thereby give up energy otherwise necessary to carry it safely past the drop-out opening.

Other novel aspects of the invention reside in certain details of construction and operation of the illustrative embodiment hereinafter described in view of the drawing, in which:

55 Fig. 1 is a side elevation of the chute with a

portion broken away to expose the drop-out opening;

Fig. 2 is a vertical median section through the chute exposing the chute passage;

Fig. 3 is a fragmentary elevational detail of the 5 movable magnet carrier and deflecting means on the side of the chute opposite to that viewed in Fig. 1; while

Fig. 4 is an enlarged perspective fragment of 10 a portion of the chute passage including the drop-out opening and the novel rebound means.

The present application is a division of our 15 pending U. S. application, Serial No. 85,879, filed June 18, 1936, for improvements in a coin and slug separating device.

A preferred embodiment of the invention includes means providing a descending coin passage, preferably in the form of a body 10 (Fig. 2) of elongated and substantially flat shape and constructed, according to one method, by securing together a pair of complementary cast plates recessed to define the tortuous and descending passage 11, the passage having two entrance openings 12 and 13 at its upper end and a reject opening 14 and acceptance opening 15 at its lower end, the latter two lower openings being spaced on opposite sides of an adjustable deflecting means 16.

Between the upper and lower terminal ends of 20 the passage 11, there is provided a sidewise drop-out opening 17 (Fig. 1) arranged opposite a depression 18 (Fig. 2) in the floor of the chute passage and in the path of a coin moving down the latter. The depression 18, it may be pointed out, is disposed in an oppositely inclined section 11' 30 of the passage just below the juncture point 19 of the latter with the upper section and hence so positioned that it is possible for a coin element to drop in a vertical line into the depression 18 35 from the upper reaches of the chute.

Improved rebound means in the form of a metallic anvil 24 is provided in the chute passage (Figs. 2 and 4) at a point above or in advance of the drop-out opening 17 and the depression 18, the arrangement being such that proper coin elements, that is, metallic coin elements of predetermined metallic content and weight, properly deposited in either of the entrance openings 12 or 13, will roll off the juncture 40 point 19 in the passage as illustrated by the dotted line trajectory A in Fig. 2 and strike the anvil with sufficient force so that they will rebound substantially along the normal trajectory B and thus be carried safely past the drop-out 45 50 55

opening 17 and depressed floor part 18 for continued passage through to the end exits 14 and 15.

The form and operation of the anvil means 24 constitutes one of the important features 5 of the invention and, as illustrated in Fig. 4, one preferred embodiment thereof includes a relatively flat or narrow block of metal, for example steel, of a thickness adapted to fit into the coin passage so that its sides are substantially flush 10 with the sides of the passage, the block thus lying within the plane of the chute body and coin passage and being positioned (Fig. 2) in the region below the juncture point 19 of the alternately directed passage sections and just above 15 the depression 18.

The anvil or block 24 has an elongated edge 25 which is beveled, sloped, or tapered, as at 26, to provide a relatively narrow and elongated rebound edge or ridge 27 pitched in a generally 20 descending direction toward the depression 18 and the adjoining lower passage section or floor 28.

The elongated rebound ridge or edge portion 27 is narrower at its top than at its base adjoining the body of the block, and the width of this 25 rebound edge 27 is preferably made less than the thickness of the edge portion of certain coin elements which the coin chute or testing device is adapted and intended to receive, the 30 purpose of this being to provide a rebound edge of wedgelike form such that spurious and illegitimate coin elements formed of a material which is softer than the metallic content of said 35 certain or proper coin elements will be dented or elastically deformed by the ridge formation when such coins drop onto the anvil, such coin elements thereby giving up energy which would otherwise assist in carrying them past the depression 18 and other testing or selecting means 40 positioned between the ends of the chute passage, such for example as the finger or gate 30 (Fig. 4) pivoted as at 31 and normally disposed by gravity in blocking position across the passage just beneath the juncture point 19 and at the 45 lower side of the depression 18.

Light-weight coin elements, such as paper discs, do not ordinarily gain sufficient momentum in leaving the juncture point 19 to cause them to follow the dotted-line trajectory A but drop down 50 in the relatively straight-line path C and fall into the depression 18 for movement out the discharge opening 17. However, certain light-weight tokens, for example, fiber washers and discs, may strike the anvil in such manner as 55 to rebound along the dotted-line trajectory D high enough to pass over the selecting means or discharge opening 17-18 were it not for the provision of the testing means or gate 30, the latter being so arranged that it will not be pivoted far enough out of the path of such tokens 60 to permit them to continue passage down the chute, proper coin elements, however, striking the finger or gate with sufficient force to pivot the latter into the dotted-line position shown in Fig. 65 2, for continued passage through the device.

Other testing means in the illustrative embodiment includes permanent magnets 35 (Figs. 1 and 2) arranged in the lower region of the device in such manner as to provide a constant 70 magnetic flux across the passage in the region just above the testing means or deflectors 16 and 16', coin elements of predetermined metallic content having eddy currents set up therein as they move through the flux or field, with a 75 consequent reaction which tends to give such

coin elements a predetermined rate of speed as they move finally toward the deflector 16 or 16' and the acceptance opening 15, other and improper coin elements being affected by passage through the magnetic field such that their travel 5 will carry them into the reject opening 14.

Another testing means includes an elongated bar magnet 36 (Fig. 3) arranged in a movable carrier 37 pivotally mounted as at 38 for movement toward and away from the side of the 10 device, the carrier normally lying close to the chute with the length of the magnet 36 fitted close to an elongated slot 39 (Fig. 2) communicating into the passage just above the juncture point 19.

A gate 40 is pivotally mounted on the opposite side of the chute body on a pintle 41 extending through lugs 42 on the gate and seated in bosses 43 on the chute. This gate likewise moves toward and away from the chute passage and constitutes a movable side wall section for the latter which, when in open position, constitutes a sidewise discharge opening above the drop-out opening 17. An elongated opening 44 is provided in the gate opposite the slot 39, and hence 20 opposite the magnet 36, for the discharge of coin elements of less than a predetermined diameter, there being a small deflecting rib 45 opposite the opening 44 to facilitate such discharge movement, and the floor portion of the passage adjacent the opening 44 preferably being inclined 30 outwardly for the same purpose.

Means including a lever 46 pivotally mounted as at 47 on a vertical edge portion of the chute and having a pin 48 projecting laterally into a 35 slotted boss 49 on the gate, may be manipulated to effect opening and closing movement of the gate 40, the latter normally remaining in closed position by force of gravity assisted by a spring 49'. A cooperating lever 50 (Fig. 3) also pivotally mounted as at 51 on the edge of the chute, and having a lateral pin 52 projecting through a slotted boss 53 on the magnet carrier, is arranged for cooperation with the lever 46 so that the magnet carrier 37 and the gate 40 will be 45 opened and closed simultaneously, responsive to 50 manipulation of the lever 46.

Yet another testing means includes a U-shaped deflecting member 55 mounted as at 56 (Fig. 1) on the gate 40 and passed reentrantly across the 55 chute passage (Fig. 2) to provide means for deflecting coin elements away from the anvil 27 for movement into the depression 18 when the gate 40 is open, the deflecting means 55 otherwise being normally out of the path of coin elements moving down the passage.

The importance of the rebound anvil 24 resides in the fact that due to its peculiar construction and location in the chute passage, certain spurious coin elements including those made of Lincoln-type metal and analogous alloys including certain mixtures of lead, tin, antimony, and zinc, all of which would otherwise be able to negotiate the passage and reach the acceptance opening 60 15, are effectively disposed of through the drop-out opening 17-18 as a result of the operation of the rebound anvil. Spurious coin elements of the latter type are dented somewhat by contact with the narrowed edge 27 with the results heretofore 65 explained. Other coin elements, whether of metal or hard fiber, are rebounded against the testing or selecting means 30, striking the latter with such force and at a point relative to its 70 pivotal mounting 31, that they are deflected back 75

into the depression 18 with consequent discharge from the chute.

Where the term "dented" is used herein or in the claims in connection with the operation of the rebound anvil, it is intended to convey not only the idea of actual physical deformation commonly understood by this term, but also the idea of momentary deformations characterizing the impact of members, one of which (e. g. the coin) is of a relatively elastic, resilient or springy material compared with the other (e. g. the anvil).

Various modifications and changes may be made in the foregoing illustrative arrangement whereby the objects and advantages of the invention may be achieved without departing from the spirit and scope thereof, and the appended claims are therefore intended to include all equivalent forms of construction and modes of operation fairly coming within their call.

Having thus described our invention, what we claim as new and desire to protect by Letters Patent is:

1. In a device of the class described including a descending coin passage down which coin elements move edgewise, selective deflecting means in the form of a rebound anvil arranged in said passage and having an elongated rebound edge disposed in the path of said coin elements and with its length extending in the direction of the normal plane of movement of said elements, said rebound edge being of a width narrower than the rim portion of coin elements deposited in said device, and constituting a ridge-like formation against which said coin elements may strike edgewise and from which said coin elements will rebound in various predetermined manners depending upon the physical characteristics thereof, said device including means arranged relative to said deflecting means for separating certain coins from others depending upon the manner in which the coins rebound from said anvil.

2. In a device of the class described including a descending coin passage down which coin elements move edgewise, deflecting means in the form of a rebound anvil arranged in said passage and having an elongated edge portion disposed in the path of said coin elements with its length extending in the direction of the plane of movement of said coin elements such that the latter may strike said edge at any point along the length thereof, said edge being beveled along its length to provide a rebound ridge of substantially wedge-like form the width of which is less than the width of the edge portion of coin elements deposited in said device and constituting an elongated striking portion from which certain coin elements will rebound in predetermined ways dependent upon their physical characteristics, said device including means arranged relative to said anvil to selectively separate certain coin elements from others depending upon the way in which said elements rebound from the anvil.

3. In a device of the class described including a passage along which coins move edgewise, a rebound anvil arranged in said passage and having an elongated rebound edge narrowed to a width less than the peripheral thickness of certain coin elements of predetermined physical character which are intended to be received and accepted by said device, said rebound edge being disposed with its length extending in the plane of movement of said coins and being pitched so as to alter the movement of coin elements striking the same and rebounding therefrom, and means arranged to function cooperably with said anvil to selectively separate certain coin elements from others dependent upon the movement of said elements in rebounding from said anvil.
